C. A. NELSON.
FIREARM.
APPLICATION FILED FEB. 17, 1915.

1,152,750.

Patented Sept. 7, 1915.

UNITED STATES PATENT OFFICE.

CHARLES A. NELSON, OF UTICA, NEW YORK, ASSIGNOR TO SAVAGE ARMS COMPANY,
OF UTICA, NEW YORK, A CORPORATION OF NEW YORK.

FIREARM.

1,152,750.

Specification of Letters Patent.

Patented Sept. 7, 1915.

Original application filed October 6, 1914, Serial No. 865,266. Divided and this application filed February 17, 1915. Serial No. 8,742.

To all whom it may concern:

Be it known that I, CHARLES A. NELSON, a citizen of the United States, residing at Utica, in the county of Oneida and State of New York, have invented certain new and useful Improvements in Firearms, of which the following is a specification.

The present application is a division of my application Serial No. 865,266, filed October 6th, 1914, and the invention herein disclosed consists in a novel means for locking the firing mechanism of a gun against release when the arm is cocked and for indicating the condition of the arm, whether

15 "safe" or "unsafe."

In the accompanying drawings, Figure 1 is a plan of a fragment of a gun having the present improvement; Fig. 2 is a left side elevation, showing the locking device in locking relation to the firing mechanism; Fig. 3 is a plan of the device, detached from the gun; Fig. 4 shows parts of the gun and the locking device in longitudinal section; and, Fig. 5 is a transverse section of the 25 gun through the locking device, which appears in the "unsafe" position.

In the breech casing *a* at the rear of the barrel *b* is arranged the breech-bolt *c* containing a striker *d* and the firing pin *e* to 30 be driven forward by the striker when the latter is released and advances under the influence of the spring *f* rearwardly supported by a suitable abutment means *g*.

The striker is held in the cocked position 35 by the trigger *h*, which is here a bell-crank lever fulcrumed in the breech casing and having a forwardly extending arm *h'* equipped with an upstanding dog *h''* formed with a rearwardly projecting lug *h'''*, giving the dog 40 substantially the character of a hook. The trigger has its arm *h'* normally held elevated by a suitable spring *i* in position to dog the striker at its shoulder *d'* when the striker is retracted with the breech-bolt in opening 45 the gun by means of the breech-bolt handle *c'*.

The locking device is a part-circular strap *j* which extends under and embraces the breech-casing and is rotatably shiftable with reference thereto for a distance determined 50 by the length of slots *k* through which extend screws *l* for retaining the strap in

place. One end of the strap is bent off to form a handle *m*. In the forward edge of the strap is formed a recess *n*. Assuming the gun to be cocked and the strap to be in 55 the position shown in Fig. 1, the location of this recess *n* is such as then to register with the lug *h'''* of the trigger, which latter is therefore free to be operated to release the striker; upon the strap being turned to the 60 position shown in Figs. 2, 4 and 5, the recess will be out of registry with the lug *h'''* of the trigger—that is, the edge of the strap will underlie the said lug,— preventing the 65 operation of the trigger.

As a means for indicating whether the firing mechanism of the gun is locked or not by the strap, suitable indices or inscriptions, as "Safe" and "Fire," may be provided on the breech casing and one end of the strap 70 in such relation that the strap will obscure "Safe" and expose "Fire" when turned to the position shown in Fig. 1 and "Safe" will be exposed by the strap and "Fire" hidden by the part of the stock *a'* which 75 flanks the breech casing (Fig. 5) when the strap is in the full line position in Figs. 2 and 5.

For holding the strap at either of its 80 limits of movement, one of two notches *o* in the strap is adapted to be engaged by a spring-pressed plug *p* guided in a cup *q* inset in the stock.

Having thus fully described my invention, what I claim as new and desire to secure by Letters Patent is:—

1. In combination, with the breech-including part of a gun, a firing mechanism, and a firing mechanism locking device embracing said part and rotative around the same 90 into and out of locking relation to said mechanism.

2. In combination, with the gun barrel having a breech-casing, a firing mechanism and a firing mechanism locking device consisting of a strap embracing said breech-casing and rotative around the same, said strap opposing in one position thereof firing movement of said mechanism and in another position having a recess registering with 100 said mechanism and thereby allowing firing movement thereof.

3. A gun having a firing mechanism and also having fixed parts one partly covered by the other, in combination with a firing mechanism controlling device movable back and forth between said parts, said device and the first-named part having indices of opposite significance one of which is adapted to be covered by said device and the other

by the second-named part alternately on back and forth movement of said device. 10

In testimony whereof I affix my signature in presence of two witnesses.

CHARLES A. NELSON.
